(57) **CLAIM**

(21) Appl. No.: **29/304,670**

The ornamental design for a turn signal lamp for a motorcycle, as shown and described.

(22) Filed: **Mar. 5, 2008**

DESCRIPTION

(30) **Foreign Application Priority Data**

FIG. 1 is a front elevational view of a turn signal lamp for a motorcycle showing my new design;

Sep. 10, 2007 (JP) 2007-024575

FIG. 2 is a rear elevational view thereof;

(51) **LOC (9) Cl.** **26-06**

FIG. 3 is a left side elevational view thereof;

(52) **U.S. Cl.** **D26/30**

FIG. 4 is a right side elevational view thereof;

(58) **Field of Classification Search** D26/28-36;

FIG. 5 is a top plan view thereof;

362/80, 81, 82, 83, 267, 269, 275, 330-340

FIG. 6 is a bottom plan view thereof;

See application file for complete search history.

FIG. 7 is a front perspective view thereof; and,

(56) **References Cited**

FIG. 8 is a rear perspective view thereof.

U.S. PATENT DOCUMENTS

The broken line showing of the environment is for illustrative purposes only and forms no part of the claimed designs.
